UNITED STATES PATENT OFFICE.

GEORGE DANIEL AND EDWARD G. LEWIS, OF MABSCOTT, WEST VIRGINIA.

LOCK.

1,300,931.

Specification of Letters Patent. Patented Apr. 15, 1919.

Application filed November 15, 1915, Serial No. 61,634. Renewed September 20, 1918. Serial No. 254,988.

To all whom it may concern:

Be it known that we, GEORGE DANIEL and EDWARD G. LEWIS, citizens of the United States, residing at Mabscott, in the county 5 of Raleigh and State of West Virginia, have invented new and useful Improvements in Locks, of which the following is a specification.

The invention relates to locks, and more 10 particularly to the class of registering car door locks.

The primary object of the invention is the provision of a lock of this character wherein on the unlocking of the door of a 15 freight car the exact time that the door is unlocked is recorded, and also the number of times of the unlocking thereof, thereby enabling a complete record to be had to entries to the car.

Another object of the invention is the provision of a lock of this character wherein the chart for the recording of the time of the unlocking of the door is detachably mounted so that it can be removed from 20 the lock, and said chart is coöperative with clock mechanism for changing the position thereof throughout an interval of twenty-four hours or more in a given or determined period of time, preferably the clock 25 mechanism being of the eight day type, thereby necessitating the winding of its 30 spring at every eighth day period.

A further object of the invention is the provision of a lock of this character wherein 35 in the construction thereof is novel in form so as to assure the recording of the time of the unlocking thereof for freeing the door to permit access or entry to the car.

Another object of the invention is the provision of a lock of this character which 40 is especially designed for use in sliding doors of railway box cars, and will clearly indicate and record each time the lock is operated in the opening and closing of the 45 car door.

A still further object of the invention is the provision of a lock of this character which is simple in construction, reliable and efficient in its operation, strong, durable, 50 and inexpensive in manufacture and installation.

With these and other objects in view, the invention consists in the construction, combination and arrangement of parts as will 55 be hereinafter fully described, illustrated

in the accompanying drawings, and pointed out in the claims hereunto appended.

In the drawings:

Figure 1 is a fragmentary side elevation of the side of a car and its sliding door, 60 showing the lock constructed in accordance with the invention applied.

Fig. 2 is an enlarged vertical longitudinal sectional view through the lock.

Fig. 3 is a fragmentary longitudinal 65 transverse sectional view showing the hasp engaged in the lock.

Fig. 4 is a fragmentary enlarged side elevation showing the indicator feed mechanism of the lock. 70

Fig. 5 is a fragmentary sectional view on the line 5—5 of Fig. 2.

Fig. 6 is a sectional view on the line 6—6 of Fig. 2.

Fig. 7 is a detail view of the markers. 75

Similar reference characters indicate corresponding parts throughout the several views in the drawings.

Referring to the drawings in detail, A designates a portion of the side of a rail- 80 way box car, and B a portion of the sliding door, which is of the ordinary well-known construction for closing the doorway in the side A of the car, as usual, and upon this side A is mounted the lock hereinafter fully 85 described.

The lock comprises a substantially rectangular shaped case 10, preferably made from metal, and is suitably fastened to the inner face of the side A, and within this 90 case is arranged a latch bolt 11 pivotally mounted at 12 intermediate its ends, and provided at one end with a hasp engaging shoulder 13, and at the other end with an upwardly curved extension 14 normally held 95 adjacent to a keyhole 15 so as to be capable of being operated against by means of a key when inserted in the keyhole 15 and turned in one direction, as will be clearly understood by those familiar with the art 100 to which this invention pertains.

Beneath the latch bolt 11 are stationary stops 16 and 17, which serve to limit the pivotal movement of the latch bolt, the latter being normally held in a certain predetermined position by means of a retractile spring 18, one end of which is connected to a lug 19 on one end of the latch bolt, while the other end of the said spring is connected to a fixed point 20 within the case. 110

The extension 14 is provided with a shoulder 21 which prevents the turning of the key in a reverse direction after it has lifted the inner end of the latch bolt 11 for 5 releasing the hasp engaging shoulder 13 for the unlocking of the lock.

One end of the lock case 10 is provided with an entrance opening 22 which is adapted to receive the pivoted end portion 23 of a hasp, 10 said hasp having a base or fixed portion 24 which is secured to the outer face of the door B of the car in any suitable manner, the portion 23 being pivoted to an intermediate portion 25 which is also pivoted to the 15 base portion 24 so that the said portion 23 can be positioned through the doorway to lie parallel with the inner face of the side A of the car for its engagement through the opening 22 in the case 10 with the latch bolt 20 11 as shown when the door B is moved to closed position.

Adjacent to the outer end of the member 23 of the hasp is provided a notch 26 adapted to receive the shoulder 13 of the latch bolt, and the end of this latch bolt is beveled as shown at 27 so that when the end of the hasp is thrust inward through the entrance slot 22 in the case it will ride against the beveled portion 27 and thereby rock the 30 latch bolt on its pivot 12 until the shoulder 13 snaps into engagement with the notch 26 in the hasp, thereby locking the door.

To unlock the door a key is inserted 35 through the keyhole 15 so as to coöperate with the extension 14 of the latch bolt, which has the effect of moving the shoulder 13 out of engagement in the notch 26 in the hasp, permitting the latter to be again withdrawn through the entrance slot 22 in the case.

40 In order to register the number of times the lock is operated there is provided a dial 28 on the outer face of the side A of the car where it may be plainly and easily observed, and in connection with said dial there is 45 employed an indicator hand 29 mounted on an arbor 30 journaled in a suitable bearing in the side of the car. Mounted fast on the arbor 30 is a ratchet wheel 31, while mounted loosely on said arbor is a disk 32 having piv- 50 otally mounted thereon a pawl 33 adapted to engage the ratchet wheel 31 for imparting an intermittent movement to the hand 29, causing the same to travel around the dial and register with the graduations thereon.

55 Connected to the disk 32 is a rod 34 which extends upward and is connected to the latch bolt 11 at the point 35 so that every time the latch bolt is rocked on its pivot motion is transmitted through the rod 34 to the disk 60 32. This causes the pawl 33 to engage the ratchet wheel 31 and move the hand 29 a certain distance. Also engaging with the teeth of the ratchet wheel 31 is a retarding spring 36 which prevents the wheel 31 from 65 rotating in the reverse direction on the up-

ward movement of the rod 34 when returning the disk 32 to normal position, thereby adding to the reliability of the registering apparatus.

Located within the lock is an eight day 70 winding clock mechanism of the ordinary well-known construction, which is held within the housing, the main spring of the said clock mechanism being wound through the medium of the winding arbor 38 which 75 extends without the side A of the car so that a winding key can be attached thereto when the occasion requires the winding of the main spring of the clock, while upon the hand arbor 39 of the clock mechanism is fixed a circular shaped or disk-like chart 40 having printed or otherwise marked on its face graduations 41 indicative of the fractions of each hour, and associated with these graduated marks are digits or numerals indicative 85 of hour periods ranging numerically from one to twenty-four or more, the chart or dial 40 being detachably held on the arbor 39 to rotate therewith through the medium of a clip 42 carried by the said arbor so that on 90 recording upon the dial or chart 40 the same can be readily removed, and this is permitted through a suitable opening in one side of the case 10 of the lock, the recording being accomplished in a manner presently described. 95

Extended from the outer face of the dial or chart 40 is an inking ribbon 43 which is in the form of a single length and is adapted to be trained over spaced guide rollers 44 for the winding of the same upon a feed roller 100 45, the said guide and feed rollers being journaled in a frame 46 supported upon a bearing 47 mounted interiorly of the case 10 of the lock, and this ribbon 43 unwinds from a reel 48 which is detachably journaled on 105 the bearing 47 below the feed roller 45. Supported at one side of the ribbon 43 and journaled in an upright 49 is a horizontally disposed rocking shaft 50, on which is mounted an arm 51 carrying a lateral extension 52 at right angles thereto, the same being disposed directly over the lower stretch of the ribbon 43, and this extension has fixed thereto a depending marking tip or pin 53 which is adapted to work against 115 the lower stretch of the ribbon 43 next to the dial or chart 40 for the marking of the same when the door is opened in a manner presently described.

Spaced from the marking tip or pin 53 120 and carried by the extension 52 is a barrel 54, through the perforated end 55 of which projects a marking tip or pin 56 which is acted upon through the medium of a coiled expansion spring 57 held within the barrel 125 54 and this tip or pin 56 is adapted to work against the lower stretch of the ribbon 43 next to the dial or chart 40 for marking the same when the door is closed, in a manner presently described. 130

The shaft 50 has fixed thereto a crank 58 to which is pivotally connected an operating rod 59, the same being also pivoted at 60 to the latch bolt 11, so that on the movement of the latch bolt in one direction the shaft 50 will be rocked for the striking of the marking tips or pins upon the ribbon 43 in their respective order for making impressions upon the chart or dial 40, which is actuated by the clock mechanism within the housing 37, thereby recording the particular time the latch bolt is moved for the unlocking of the lock to free the door for the opening thereof and also the particular time the door is closed and locked. The shaft 50, at the end connected with the crank 58, has mounted thereon a ratchet dog 61 which engages the teeth of a ratchet wheel 62 fixed to the feed roller 45 so that on the movement of the shaft 50 the ribbon 43 will be fed intermittently to prevent the tips or pins 53 and 56 from striking one point of the ribbon during the working of the lock.

For a given period of time a complete record can be had upon the dial or chart 40 as to the number of times the lock has been unlatched and latched so as to determine the entrance to the car and also as to the extent of time the door has remained open, as will be clearly apparent and also the exact time that the door has been closed.

In the operation of the lock, assuming that the door is normally open and on the closing thereof the latch bolt 11 trips the keeper or hasp which causes a slight rocking movement of the said bolt, thereby bringing the marking tip or pin 56 into a position to strike the ribbon 43 and the making of an impression upon the dial or chart, thus in this manner indicating the time of the closing of the door. Now when a key is inserted in the lock for the opening of the door the latch bolt 11 rocks to a greater degree than in engaging the hasp so that the marking tip or pin 53 is brought into engagement with the ribbon 43 and an impression is made upon the chart, thereby indicating the time of the opening of the door, it being seen that the marking tip or pin 56 will become retracted in the barrel 54 against the resistance of the spring 57 therein so as not to

interfere with the recording of the time of the opening of the door by an impression from the marking tip 53 upon the chart.

From the foregoing description, taken in connection with the accompanying drawings, the construction and manner of operation of the device will be readily apparent, and a more extended description has, therefore, been omitted.

60

What is claimed is:—

A lock of the character described comprising a casing, a key operated locking bolt pivotally mounted within the casing, a chart support interiorly of the casing, means for automatically rotating the chart support, a flat disk-like chart removably fitted upon the holder and having indicia thereon indicative of hours and fractions thereof, a frame mounted interiorly of the casing, a feed roller journaled in the frame, guide rollers journaled in the frame, an inking ribbon trained over the guide rollers to have a portion overlie the chart and connected with the feed roller for movement thereby, a rock shaft journaled adjacent the frame and having a crank, a connection between the crank and the bolt for the simultaneous movement of the shaft and bolt, an extension on the shaft, a rigid marking tip carried by the extension and movable into contact with the portion of the ribbon extending over the chart to act thereon for the making of an impression upon the chart on the rocking of the shaft in one direction, a ratchet wheel connected with the feed roller, a ratchet member actuated by the shaft and engageable with the ratchet wheel for imparting movement thereto, and a resiliently supported marking tip carried by the extension and adapted for contact with the ribbon, said resiliently supported marking tip being normally extended beyond the first named marking tip.

In testimony whereof we affix our signatures in presence of two witnesses.
